UNITED STATES PATENT OFFICE.

PARKER DEXTER, OF CLINTON, IOWA.

IMPROVED MACHINE FOR BUNCHING AND PRESSING SHINGLES.

Specification forming part of Letters Patent No. **38,036**, dated March 31, 1863.

To all whom it may concern:

Be it known that I, PARKER DEXTER, of Clinton, in the county of Clinton and State of Iowa, have invented a new and Improved Machine for Bunching and Pressing Shingles; and I do hereby declare that the following is a full, clear, and exact description of the same, reference being had to the accompanying drawings, making a part of this specification, in which—

Figure 1 is a side view of my invention; Fig. 2, a plan or top view of the same; Fig. 3, a transverse vertical section of the same, taken in the line *x x*, Fig. 1. Fig. 4 is a perspective view of a bunch of shingles.

Similar letters of reference indicate corresponding parts in the several figures.

The object of this invention is to obtain a machine of simple and economical construction by which a suitable number of shingles may be adjusted compactly together and bunched or bound together so as to form a bundle.

The invention consists in the employment or use of two folding end boards or plates attached to a suitable frame and used in connection with eccentrics placed on a suitable shaft in the frame and arranged with clamps, as hereinafter fully shown and described.

To enable those skilled in the art to fully understand and construct my invention, I will proceed to describe it.

A represents a horizontal frame, which is constructed of two parallel bars, *a a*, connected by cross-ties *b b*. On one end of this frame there is secured a board, *c*, which is designed to serve as a seat for the operator.

B is a shaft which is fitted transversely in the frame *A*, and has four eccentrics, *C C D D*, upon it. The eccentrics *C C* are at the outer sides of the bars *a a* of the frame *A*, and the eccentrics *D D* at the inner sides of the same, the eccentrics *C* being in a reverse position on the shaft *B*, to the eccentrics *D*, as shown in Fig. 3. On one end of this shaft *B* there is placed a lever, *E*. In each bar *a*, directly over the shaft *B* there is made a vertical slot or opening, *b'*, in which loose or sliding plates *F* are fitted, said plates projecting over the eccentrics *D D*, as shown clearly in Fig. 3.

G G are vertical bars or yokes, the lower parts of which are fitted on vertical guides *c' c'* at the outer sides of the bars *a a*, and are allowed to slide freely up and down on them.

The lower parts of these bars or yokes are each provided with a recess, *d*, at their outer sides, said recesses having their upper and lower edges parallel with each other. The eccentrics *C C* work within the recesses *d d* of the bars or yokes *G G*, as shown clearly in Fig. 3. In the upper parts of the bars or yokes *G G* there are fitted screws *H H*—one in each—and on the upper ends of said screws there are horizontal, bent, or right-angular bars *I I*, one on each. The bars *I I*, it will be seen, may be raised or lowered by turning the screws *H H*.

J J represent two end boards or plates which extend the whole width of the frame *A*. These end boards have vertical metal angle-plates *e* attached to their ends, and the lower ends of said plates *e* are attached by joints or hinges *f* to upright plates *g*, which are secured to the sides of the frame *A*. The lower ends of the plates *e*, at one side of the end boards and below the joints or hinges *f*, are connected by joints or pivots *h* to arms *i i*, the inner ends of which are connected by pivots *j j* to levers *k k*, which are secured by fulcrum-pins *l l* to the side of the frame *A*, and have toothed segments *m m* at their inner ends, said segments gearing into vertical racks *n n* at the sides of the lower parts of the vertical bars and yokes *G G*. (See more particularly Fig. 1.)

The operation is as follows: The lever *E* is in the first place so turned or adjusted as to bring the end boards *J J* in a vertical position, as shown in blue tint in Fig. 1, and the lower cross-bar, *o*, of the band (see Fig. 4) is placed on the plates *F* in the slots or openings *b'*. The shingles are then laid on the frame *A*, between the end boards, *J J*, the buts being outward and resting on the cross-ties *b b* and the points or inner ends overlapping each other and supported by the cross-bar *o*. The end boards, *J J*, form guides to admit of the shingles being laid in proper position, and when a sufficient number of shingles have been laid on the frame *A* to form a bundle, the operator raises the lever *E* and thereby turns outward the end boards, *J J*, to a horizontal position, as indicated by the red outline in Fig. 1. Simultaneously with this outward movement of the end boards, *J J*, which is produced by the racks *n n* of the yokes *G G*, the segment-levers *k k*, and arms *i i*, the eccentrics *C C D D* respectively draw down the yokes *G G* and bars *I I* and elevate the plates *F*, the latter pressing upward

the lower cross-bar, *o*, of the band, and the bars *I* pressing down upon the upper bar, *p*, of the same. By this means the shingles are compressed and compacted snugly together, and when this is accomplished the operator nails the upper ends of the sides *q* of the band to the ends of the upper band, *o*, the lower ends to the sides *q* having been previously nailed to the ends of the lower bar, *o*. The sides *q* may be of hoop-iron.

I would remark that at the commencement of the operation the bars *I* are turned outward, so that they will not interfere with the placing of the shingles on the frame.

Having thus described my invention, what I claim as new, and desire to secure by Letters Patent, is—

The movable or adjustable end boards, *J J*, in combination with the bars or yokes *G G*, bars *H H*, and eccentrics *C C D D*, on shaft *B*, all arranged and applied to the frame *A*, to operate substantially as and for the purpose herein set forth.

PARKER DEXTER.
